(57) **CLAIM**

The ornamental design for a light cover as shown and described.

DESCRIPTION

FIG. 1 is a front and left side perspective view of a light cover, showing our new design;

FIG. 2 is a rear and right side perspective view thereof;

FIG. 3 is a front and right side perspective view thereof;

FIG. 4 is a rear and left side perspective view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a right side elevational view thereof;

FIG. 10 is a left side elevational view thereof; and,

FIG. 11 is a perspective view thereof wherein the light cover is shown in a condition of use with additional broken line environment.

De-emphasized portions using lightened halftone shading and encapsulated with broken lines shown in the drawings depict portions of the light cover that form no part of the claimed design.

The grayscale shading of the drawings depict the shape of the three-dimensional surface and does not represent any particular colors.
